UNITED STATES PATENT OFFICE.

WILLIAM C. LEASURE, OF STEUBENVILLE, OHIO.

DESIGN FOR A LAMP-SHADE.

44,709.

Specification for Design.

Patented Sept. 30, 1913.

Application filed July 19, 1913. Serial No. 780,079. Term of patent 7 years.

To all whom it may concern:

Be it known that I, WILLIAM C. LEASURE, a citizen of the United States, residing at Steubenville, in the county of Jefferson and State of Ohio, have invented a new, original, and ornamental Design for a Lamp-Shade, of which the following is a specification, reference being had to the accompanying drawing, forming part thereof.

Figure 1 is a side view and Fig. 2 is a cross section of a lamp shade, showing my new design.

I claim:

The ornamental design for a lamp shade as shown.

WILLIAM C. LEASURE.

In presence of—

R. B. JEW,

L. GRIFFITH.
